CLAIM

The ornamental design for a medical device system and removable connectors set, as shown and described.

DESCRIPTION

FIG. 1 is a perspective view of the medical device system and removable connectors set;

FIG. 2 is a front view of the medical device system and removable connectors set with the connectors removed for ease of illustration;

FIG. 3 is a back view thereof;

FIG. 4 is a right side view thereof;

FIG. 5 is a left side view thereof;

FIG. 6 is a top view thereof; and

FIG. 7 is a bottom view thereof;

FIG. 8 is a perspective view of a first connector compatible with the medical device system of FIG. 1;

FIG. 9 is a front view thereof;

FIG. 10 is a back view thereof;

FIG. 11 is a right side view thereof;

FIG. 12 is a left side view thereof;

FIG. 13 is a top view thereof; and

FIG. 14 is a bottom view thereof;

FIG. 15 is a perspective view of a second connector compatible with the medical device system of FIG. 1;

FIG. 16 is a front view thereof;

FIG. 17 is a back view thereof;

FIG. 18 is a right side view thereof;

FIG. 19 is a left side view thereof;

FIG. 20 is a top view thereof; and,

FIG. 21 is a bottom view thereof.

(Continued)

Features shown in broken lines form no part of the design as claimed.
